FEEDING MECHANISM

Filed May 31, 1923

*Inventor: Charles F. Osgood.
by Grace L. Osgood. Atty.*

UNITED STATES PATENT OFFICE

CHARLES F. OSGOOD, OF CLAREMONT, NEW HAMPSHIRE, ASSIGNOR TO SULLIVAN MACHINERY COMPANY, A CORPORATION OF MASSACHUSETTS

FEEDING MECHANISM

Application filed May 31, 1923. Serial No. 642,489.

My invention relates to feeding mechanisms, and more particularly to feeding mechanisms for fluid pressure rock drills of the drifter type.

5 An object of my invention is to provide an improved feeding mechanism. A further object of my invention is to provide an improved feeding mechanism of a type adapted for use with fluid pressure rock drills of the drifter type whereby a large feeding capacity is obtained while retaining a compact, light construction. Other objects and advantages of my invention will hereinafter more fully appear.

15 In the accompanying drawings I have shown for purposes of illustration one form which my invention may assume in practice.

In these drawings,—

Fig. 1 is a side elevation, partially in central longitudinal section, of a drifter type drill incorporating my improved feed mechanism.

Fig. 2 is a transverse section taken on line 2—2 of Fig. 1.

25 In this illustrative form of my invention I have shown the same used in connection with a drilling motor 1, herein of the valveless percussive type, comprising a cylinder 2 having a piston (not shown) reciprocable therein in a well known manner, adapted to percussively actuate a drill steel 3 suitably carried in the front end of the drilling motor under the control of a throttle valve mechanism 3'.

35 The cylinder 2 is herein provided with gibs 4 which cooperate with grooves 5 in guides 6 formed on an intermediate cradle member 7. The cradle member 7 has gibs 8 formed thereon which cooperate with grooves 9 in guides 10 on a shell 11 which is mounted on a trunnion 12. Carried in a boss 13 formed integral with the cylinder 2 is a stationary feed nut 14 which cooperates with a rotatable feed screw 15, suitably journaled in support

45 means (not shown) in the cradle member 7, and having a longitudinally disposed bore 16 formed therein. Arranged in a boss 17 formed integral with the intermediate cradle member 7 is a stationary feed nut 18 which

50 journaled in supports 20 suitably secured, herein by bolt connections 21, to the shell 11. Also journaled in the left hand support 20 is a rod 22, slidably mounted within the bore 16 in the feed screw 15 but rotatable therewith by means of keyways 23 cut along its length 55 cooperating with keys 24 fixed within the feed screw. Rigidly secured to a gear 27, herein by a bolt connection 25, is a handle 26. Loosely mounted on the shaft 22 is the gear 27 which meshes with a gear 28 loosely journaled on an extension 29 of the feed screw 19. The gear 27 is adapted to be connected to the rod 22 by means of a suitable clutch 30, herein a dental clutch, while the gear 28 is connected to the feed screw 19 by means of a similar clutch 31.

55 The mode of operation of my invention is as follows: The trunnion 12 is suitably clamped to a tripod or column (not shown) with the drill steel 3 adjacent the working face. Fluid pressure is then admitted to the drill motor 1 through the throttle valve mechanism 3', from any suitable source of supply, and the steel 3 is percussively actuated. The operator then throws in the clutch 31 and by rotating the handle 26 the drill motor and the intermediate cradle mounting are fed simultaneously forward. When the screw 19 reaches its limit of feeding capacity, the clutch 31 is thrown out and the clutch 30 is thrown in and by again rotating the handle 26 the drilling motor 1 is fed outwardly relative to the cradle member 7 and the shell 11. When it is desired to return the drill, both of the clutches 30 and 31 are thrown in, collapsing the drill at a higher speed. It is clearly evident from the foregoing description that the cradle and drill may be fed simultaneously or independently 60 relative to the shell 11 and that a feed of large capacity is obtained in a mechanism substantially no longer than the drilling motor itself.

65 While I have in this application specifically described one form which my invention may assume in practice, it will be understood that this form of the same is shown for purposes of illustration and that the invention may be modified and embodied in various 70

other forms without departing from its spirit or the scope of the appended claims.

What I claim as new and desire to secure by Letters Patent is:

1. In a rock drill, a drilling tool, a cradle therefor having guideways along which said tool is slidable, a guide shell for supporting said tool and cradle and having guideways along which said cradle is slid-
able, means to feed said drilling tool relative to said cradle, and means to feed said cradle relative to said shell, said feeding means being simultaneously operable to effect feed of the drilling tool relative to said shell during drilling and including a common operating element mounted on said shell to effect simultaneous feed of said cradle relative to said shell and said tool relative to said cradle, said operating element remaining, as regards bodily movement, stationary with said shell during feeding of said cradle.

2. In a rock drill, a drilling tool, a cradle therefor having guideways along which said tool is slidable, a guide shell for supporting said tool and cradle and having guideways along which said cradle is slidable, and feeding means for said drilling tool including a common operating element mounted on said shell operable to effect simultaneous feed of said cradle relative to said shell and said tool relative to said cradle or feed of one of said elements independently of the other, said operating element remaining, as regards bodily movement, stationary with said shell during feeding of said cradle.

3. In a rock drill, a drilling tool, a cradle having guideways along which said drilling tool is slidable, a guide shell having guide-
ways along which said cradle is slidable, means for feeding said drilling tool relative to said cradle including a feed screw carried by one of said elements and a cooperating feed nut carried by said other element, and means for feeding said cradle relative to said shell including a feed screw carried by one of said elements and a feed nut carried by said other element, said feed screw remaining stationary as to axial movement during feeding of said cradle and said feed-
ing means being both operative to effect feeding of said drilling tool toward the work during drilling.

4. In a rock drill, a drilling tool, a cradle having guideways along which said drilling tool is slidable, a guide shell having guideways along which said cradle is slidable, means for feeding said drilling tool relative to said cradle including a feed nut carried by said tool and a cooperating feed screw carried by said cradle, and means for feeding said cradle relative to said guide shell including a feed nut carried by said cradle and a cooperating feed screw carried by said shell and remaining stationary

therewith as to axial movement during feeding of said cradle, both of said feeding means being operative to effect feed of said drilling tool toward the work during drilling.

5. In a rock drill, a drilling tool, a cradle having guideways along which said drilling tool is slidable, a guide shell having guide-
ways along which said cradle is slidable, means for feeding said drilling tool relative to said cradle including a feed screw carried by one of said elements and a cooperating feed nut carried by said other element, means for feeding said cradle relative to said shell including a feed screw carried by one of said elements and a feed nut carried by said other element, and means including common mechanism carried by said shell and relative to which said cradle and drilling tool are bodily movable during feeding thereof for operating said feeding elements for both said drilling tool and cradle to cause either or both of the same to effect feed of said drilling tool toward the work during drilling.

6. In a rock drill, a drilling tool, a cradle having guideways along which said drilling tool is slidable, a guide shell having guideways along which said cradle is slidable, means for feeding said drilling tool relative to said cradle including a feed nut carried by said tool and a cooperating feed screw carried by said cradle, means for feeding said cradle relative to said guide shell including a feed nut carried by said cradle and a cooperating feed screw carried by said shell, and means including common mechanism carried by said shell and relative to which said cradle and drilling tool are bodily movable during feeding thereof for operating said feeding elements for both said drilling tool and cradle to cause either or both of the same to effect feed of said drilling tool toward the work during drilling.

7. In a rock drill, a drilling tool, a cradle, a guide shell, gibs formed on said cradle and tool adapted to cooperate with guides formed on said shell and cradle respectively, separate feeding means for said drilling tool and cradle respectively, each including a feed screw and cooperating feed nut, and a single manual operating handle for effecting relative rotation between the screws and nuts of said feeding means to cause either or both of the same to effect feed of said drilling tool during drilling, said handle remaining stationary, as to bodily movement, during feeding of said tool and said cradle.

In testimony whereof I affix my signature.

CHARLES F. OSGOOD.
